US00D732020S

(12) **United States Design Patent**
Seoc

(10) **Patent No.:** **US D732,020 S**
(45) **Date of Patent:** **** Jun. 16, 2015**

(54) **ALL-IN-ONE COMPUTER**

(71) Applicant: **SAMSUNG ELECTRONICS CO., LTD.**, Suwon-si, Gyeonggi-do (KR)

(72) Inventor: **Ho-Young Seoc**, Yongin-si (KR)

(73) Assignee: **SAMSUNG ELECTRONICS CO., LTD.** (KR)

(**) Term: **14 Years**

(21) Appl. No.: **29/468,403**

(22) Filed: **Sep. 30, 2013**

(30) **Foreign Application Priority Data**

Apr. 1, 2013 (KR) 30-2013-0016514

(57) **CLAIM**

The ornamental design for an all-in-one computer, as shown and described.

DESCRIPTION

FIG. 1 is a top front perspective view of an all-in-one computer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another right side view thereof, showing a support cover partially open and a sliding cover moved slightly downward; and,

FIG. 9 is another right side view thereof, showing the support cover fully open to support the all-in-one computer.

The broken lines shown in the drawings represent portions of the all-in-one computer form that no part of the claimed design.

1 Claim, 4 Drawing Sheets
